UNITED STATES PATENT OFFICE

150,880

DESIGN FOR A BROOCH OR THE LIKE

Thornton J. Manry, Kansas City, Mo., assignor to The Green Company, Incorporated, Kansas
City, Mo., a corporation of Missouri

Application October 13, 1947, Serial No. 141,878

Term of patent 14 years

(Cl. D45—19)

To all whom it may concern:

Be it known that I, Thornton J. Manry, a citizen of the United States, residing at Kansas City, in the county of Jackson and State of Missouri, have invented a new, original, and ornamental Design for a Brooch or the like, of which the following is a specification, reference being had to the accompanying drawing, forming a part thereof.

Figure 1 is a face view of a brooch or the like, showing my new design.

Fig. 2 is a top edge elevational view thereof; and

Fig. 3 is a rear elevational view thereof.

I claim:

The ornamental design for a brooch or the like, as shown.
